DESIGN FOR A PNEUMATIC TIRE

Ralph S. Lombard, Detroit, Mich., assignor to
United States Rubber Company, New York,
N. Y., a corporation of New Jersey

Application October 29, 1940, Serial No. 96,155

Term of patent 14 years

To all whom it may concern:

Be it known that I, Ralph S. Lombard, a citizen of the United States of America, residing in Detroit, county of Wayne, and State of Michigan, have invented a new, original, and ornamental Design for a Pneumatic Tire, of which the following is a specification, reference being had to the accompanying drawing, forming part thereof, wherein:

Fig. 1 is a perspective view of a tire, a portion only being illustrated in solid lines, showing my new design;

Fig. 2 is an enlarged, side elevational view of a portion of the tire;

Fig. 3 is a fragmentary transverse view, in section, taken along lines III—III of Fig. 2; and

Fig. 4 is a fragmentary transverse view, in section, taken along lines IV—IV of Fig. 2.

I claim:

The ornamental design for a pneumatic tire, as shown.

RALPH S. LOMBARD.
